UNITED STATES PATENT OFFICE.

BERNHARDT SCHIBLER, JR., OF PATERSON, NEW JERSEY.

TOBACCO-PIPE.

SPECIFICATION forming part of Letters Patent No. 793,470, dated June 27, 1905.

Application filed December 31, 1904. Serial No. 239,110.

To all whom it may concern:

Be it known that I, BERNHARDT SCHIBLER, Jr., a citizen of the United States, residing in Paterson, Passaic county, New Jersey, have 5 invented certain new and useful Improvements in Tobacco-Pipes; and I do hereby declare the following to be a full, clear, and exact description of the invention, such as will enable others skilled in the art to which it appertains to make 10 and use the same, reference being had to the accompanying drawings, and to letters of reference marked thereon, which form a part of this specification.

My invention has for its object to provide 15 a tobacco-pipe with a simple, inconspicuous, and effective means for clearing it of the mass of ashes and half-smoked tobacco which is left therein after use and which if attempted to be removed by striking the pipe against some 20 rigid surface often leads to damage to the pipe, especially if made of meerschaum.

My invention will be found fully illustrated 25 in the accompanying drawings, wherein—

Figure 1 illustrates a pipe with its bowl 30 portion in section, so as to show the device of my invention. Fig. 2 is a plan view of the bowl portion of the pipe with said device in place therein. Fig. 3 illustrates a detail, and Fig. 4 shows a modified form of the invention.

In the bowl *a* of the pipe *b* I place a spiral 35 *c*, formed, say, of wire and preferably of such diameter as to snugly fit the bowl. The lower end portion *d* of the spiral is straight and is in the spiral's axis, being journaled in a hole *e* in the bottom of the bowl, through which it protrudes. Said end portion has a shoulder *f*, which abuts against the inside surface 40 of the bowl, and at its protruding extremity, which is squared, as at *g*, it carries a knurl or milled finger-piece *h*, which may have a 45 split hub *i*, receiving the squared extremity of the portion *d* of the spiral. This means of

attaching the knurl permits the spirals to be made and sold separately from the pipes, and to accommodate various sizes of pipes the spiral may have a radius a little larger than the radius of the average pipe-bowl, its inherent compressibility being relied on to make it fit bowls of the smaller sizes.

In Fig. 4 the spiral is shown as made of a 50 spirally-wound strip of metal having its forward edge *j* sharp and set snugly against the inside surface of the pipe-bowl. This spiral is calculated to better clear away charred tobacco, which cakes up the surface of the bowl. 55 In this figure is also shown a bushing *k*, having its ends expanded to secure it in the bowl, as at *l*, said bushing serving as a bearing for the spiral.

Having thus fully described my invention, 60 what I claim, and desire to secure by Letters Patent of the United States, is—

1. The combination, with a tobacco-pipe, of a spiral for clearing out the bowl thereof arranged to rotate in said bowl with its axis coincident with that of the bowl, said spiral having an axial projection protruding through the bowl-bottom and forming a handle for rotating said spiral, substantially as described. 65

2. The combination, with a tobacco-pipe, of a spiral for clearing out the bowl thereof arranged to rotate in said bowl with its axis coincident with that of the bowl, said spiral having an axial projection protruding through the bowl-bottom, and a finger-piece attached 70 to the protruding end of said projection, substantially as described.

In testimony that I claim the foregoing I have hereunto set my hand this 16th day of November, 1904.

BERNHARDT SCHIBLER, JR.
